UNITED STATES PATENT OFFICE.

GEORGE P. BARD, OF YOUNGSTOWN, OHIO.

PRESSED CORRUGATED SHEET-METAL ANNEALING-BOX.

1,328,030.

Specification of Letters Patent. Patented Jan. 13, 1920.

Application filed May 10, 1919. Serial No. 296,139.

To all whom it may concern:

Be it known that I, GEORGE P. BARD, a citizen of the United States, residing at Youngstown, in the county of Mahoning and State of Ohio, have invented certain new and useful Improvements in Pressed Corrugated Sheet-Metal Annealing-Boxes, of which the following is a specification, reference being had therein to the accompanying drawing.

This invention relates to improvements in pressed corrugated sheet metal annealing boxes, and the primary object of the invention is to construct a practical pressed corrugated sheet metal annealing box whereby a cheap structure is produced.

The specific object of the invention is to construct the box of a body portion composed of two corrugated end portions and the main corrugated body portion so shaped that the edges of the ends and main body portion fit together to be welded, and the lower ends of the main body portion and end portions so shaped that they provide downwardly extending welding surfaces substantially flush with each other to receive an L-shaped strengthening and supporting base rim welded to the said lower welding portions of the body and ends, making a simple, cheap and effective structure.

Other specific objects of the invention will appear from the following description.

In the accompanying drawings—

Figure 1 is a side elevation of my improved corrugated sheet metal annealing box.

Fig. 2 is a top plan view of Fig. 1.

Fig. 3 is an end elevation of the box.

Fig. 4 is a detached end elevation of one of the box ends.

Fig. 5 is a sectional view on the line 5—5 of Fig. 3.

My improved corrugated sheet metal annealing box is preferably composed of commercial open hearth steel and it is made up of four parts, viz., a main body portion 1; two end portions 2 and an L-shaped combined strengthening and base portion rim 3.

The main body portion, as here shown, is made up of a single sheet of metal, which is bent into approximately an inverted U-shape with transverse corrugations 4. The ends of the corrugations 4 begin at the points 5, above the lower edge of the main body portion, leaving a straight downwardly extending lower welding edge 6. These corruga-

tions are uniform in width across the top of the body portion 1, as shown at 7, and gradually narrow or taper at the sides of the box to their lower ends 5, as shown in Fig. 1.

The ends 2 of the box are made up of corrugated plates, the corrugations of the ends made of different lengths, the longest being in the center of the plate and the corrugations at the side of the center being made substantially shorter at their upper ends, thus bringing their upper ends in different horizontal planes at the side of the center corrugation, while their lower ends are in the same horizontal plane. These ends 2, have their lower ends 8 straight and in substantially the original plane of the sheet from which the ends are pressed or stamped, which brings their ends 8 substantially flush with the straight lower ends 6 of the main body portion 1, while the sides and curved tops of the end pieces 2 are bent inward beyond the plane of their lower ends 8, as shown at 9, to provide lapping welding engaging surfaces 10 between the sides and top 9 and the bend of the end corrugation of the main body 1.

By reason of this specific construction, the lower ends of the main body portion and its ends 2 form a welding surface 11, which is substantially flush for the purpose of receiving an outside L-shaped combined strengthening angle iron and rim 12. This angle iron 12 is preferably composed of a single piece bent into a contour corresponding to and fitting outside of the end portions 8 and 6 of the main body portion 1 and its ends 2, and the ends of the bent angle iron 12 are welded together at the point 13.

The corrugations 14 of the end pieces 2 have their lower ends 15 above the straight ends 8, and substantially in the same horizontal plane, whereas the upper ends of the corrugations at each side of the center one are in different horizontal planes, thus constituting corrugations of various lengths.

My construction of box is composed of few parts and each part is of a shape which is practical to stamp or press and shape to assemble, and when assembled, produce an effective annealing box at a relative economical expenditure, while at the same time it produces a box which will effectively stand up under the intense heat to which such boxes are subjected. It is understood, of course, by those skilled in the art that all annealing boxes are necessarily compara-

tively short lived, because of the intense heat surrounding them when in use, irrespective of the material of which it is constructed. In view of the unavoidable short life of such boxes, a box which is of a practical cheap construction is highly desirable, and boxes of the construction here shown and described will be found to be substantially long lived to make it cheap, as compared with other types of annealing boxes and their life under practical use.

From the foregoing description, it will be noted that the main body portion and the end pieces have their lower edges straight, or, in other words, in the same or substantially the same straight plane as the plates from which they are shaped, and by reason of this construction the straight surface is formed to receive the inner straight walled L-shaped angle iron rim 12, as before described. Access to the inside of the box is had through its open bottom.

The corrugations in the main body portion 1 and ends 2 are for the purpose of providing for the expansion and contraction of the box, due to it being intensely heated and then cooled and vice versa, and also provide strengthening ribs, so to speak, for supporting the top of the box against undue caving in or warping.

Having thus described my invention, what I claim and desire to secure by Letters Patent is:—

1. An improved annealing box composed essentially of an inverted U-shaped body portion having transversely arranged corrugations with their ends stopping above the lower edge of the U-shaped portion, separate end pieces with inwardly curved sides and ends to fit the outer portions of the outer corrugations of the main body portion, thus forming engaging welded surfaces and having straight lower edges and a surrounding L-shaped combined strengthening and base piece fitting the straight lower edges of the ends and main body portion and welded thereto.

2. An improved annealing box, composed of corrugated sheet metal, an inverted U-shaped main body-portion having continuous transverse corrugations with their ends stopped above the lower edge thereof, separate end pieces having longitudinal corrugations with their lower ends stopping above the lower ends of the said end pieces, whereby the body portion and the ends have lower straight edges, and a surrounding L-shaped base plate having its vertical web fitting against the said straight portions and welded thereto with its horizontal web extending outward, the sides and tops of the end pieces curved inward to fit against the curved ends of the body portion and welded thereto.

3. An improved corrugated sheet metal annealing box, comprising a U-shaped body portion having transverse corrugations ending above its lower edge to form a straight lower edge, end pieces having straight lower edges corresponding to the lower edge of the body portion and corrugations, the sides and tops of the end pieces curved inward beyond their straight lower ends and welded to the curved ends of the main body portion, and an L-shaped base bar fitting the outsides of the straight portions of the ends and body and welded thereto.

4. An improved corrugated sheet metal annealing box, comprising an inverted U-shaped body portion having transverse corrugations ending above its lower edge to form a straight lower welding portion, separate end pieces having a straight lower edge corresponding to the straight lower edge of the body portion and also having vertical corrugations, the adjacent edges of the end pieces and body portion having correspondingly formed overlapping welded portions, and a strengthening base iron surrounding and welded to the straight lower edges of the body portion and end pieces.

In testimony whereof I hereunto affix my signature.

GEORGE P. BARD.
